United States Patent Office

LOUIS GODDU, OF BOSTON, MASSACHUSETTS, ASSIGNOR TO ELMER TOWNSEND, OF SAME PLACE.

Letters Patent No. 97,191, dated November 23, 1869.

IMPROVEMENT IN MACHINES FOR NAILING SHOE-SOLES WITH WIRE.

The Schedule referred to in these Letters Patent and making part of the same.

To all persons to whom these presents may come:

Be it known that I, LOUIS GODDU, a citizen of the Dominion of Canada, having resided the year preceding in the United States of America, and made oath of intention to become a citizen thereof, and being now a resident of Boston, of the county of Suffolk, and State of Massachusetts, have made a new and useful invention, having reference to the Nailing of Shoe-Soles, or various other Articles, with Wire; and I do hereby declare the same to be fully described in the following specification, and represented in the accompanying drawings, appurtenant thereto.

Of such drawings—

Figure 1 is a front elevation of a machine embodying my invention.

Figure 2 is a side view of it.

Figure 3 is a longitudinal section of it, taken through the transerrer.

Figure 4 is another such section, taken through the movable cutter.

Figure 5 is a transverse and vertical section, taken through the feed-wheel.

In this machine, the feeding of the wire into the transerrer, as well as the severing of the nail from the wire, and transferring of the nail to the nail-driver, and driving such nail into a sole or other body, are effected by mechanism, combined with and actuated by the shank of the nail-driver, during the upward and downward movements thereof.

The stock of the machine is shown at A, it being formed so as to be readily grasped in one hand of an operative.

It has a nose-piece, I, and an adjustable edge-gauge, K, as hereinafter mentioned.

It also has a transerrer, C, and a movable knifecarrier or lever, H.

There is also, within the frame, a curved passage, x, for the reception of the strip of wire, z, and the conveyance of it from the feed-wheels into the transerrer.

The shank of the nail-driver a is shown at B, such shank being provided with a head, b.

C and D are the feed-wheels, or wheels for feeding the strip z of wire along through the strip-passage x, as fast as may be necessary, there being, to the larger of these feed-wheels, a ratchet, d, which, fixed to the said feed-wheel, is supported on a stationary pivot or journal, e.

The lesser feed-wheel is simply a presser-wheel, its journals being supported by a spring, f, which presses the wheel closely against the strip of wire, so as to crowd it up to the milled periphery of the larger feed-wheel.

A rocker-lever, F, formed in manner as represented in the drawings, and arranged alongside of the said

ratchet, and having the journal-pin e as a fulcrum, carries, at its upper part, a pawl, f', to operate with the dentated periphery of the ratchet.

During each descent of the shank of the nail-driver, a cammed and slotted projection, or arm, G, extended from such shank, and formed in manner as exhibited, will be driven against the lever F, and will turn it on its fulcrum, in a manner to force the pawl against the ratchet, and cause it to be revolved more or less, so as to feed the wire forward.

A spring, H', suitably applied to the stock and the lever, serves to effect the retreat or return movement of the lever, and to move such lever until a projection, g, of it is brought up against a stop, h, extended from the nail-gauge I'.

This nail-gauge I' is an elastic arm, pivoted, at one end, to the stock A, the pivot being shown at i.

When turned on its fulcrum, such arm passes over a curved rack or notched projection, k, extended from the stock in manner as represented.

The arm should be made with a projection or rib on its under surface, such rib being to enter either of the notches l of the rack k, and engage the arm therewith, so as to arrest the stop h in position.

By means of the notched projection or rib k, the catch-lever or nail-gauge I' and the stop h, the extent of back movement of the pawl of the lever F may be determined, for the purpose of effecting, by the forward movement of the lever, the proper advance or feeding of the wire.

As the nail-wire is moved forward, it passes into the transerrer C, whose lower part, q, is tubular, to receive the wire.

This transerrer is a lever, arranged within and pivoted to the stock, its fulcrum being shown at r.

The lever is moved in one direction by the nail-driver shank while descending, the reverse movement of the transerrer being effected by a spring, s, fixed to the stock, and arranged, relatively to the transerrer, in manner as exhibited in the drawings.

The lower end of the shank of the nail-driver is semispherical, as shown at t, for the purpose of actuating the transerrer, whose upper arm is cam-shaped, as shown at u, to cause the transerrer to be actuated by the shank.

Furthermore, there is within the shank a stationary knife, w, to operate with a movable cutter or knife, v, carried by a lever, H.

This lever is arranged within and pivoted to the shank, its fulcrum being shown at w.

The upper arm of this lever is bevelled, as shown at x, to cause the lever to be moved in one direction, viz., such as to advance its knife up to the stationary knife by the nail-driver carrier during its descent.

A spring, y, projected from the stock and against

the lever, serves to effect a reverse movement of the cutter lever, at the proper time or times.

To the nail-driver and the stock, a spring, z' , is applied, its purpose being to raise the shank or carrier of the driver after each descent of it.

At the lower part of the stock, and projected therefrom, and formed in manner as represented in the drawings, is what may be termed the nose-piece I . This, at its lower end, is to rest directly on the sole to be nailed; an adjustable gauge, K , fastened to the stock, and arranged with the nose-piece, in manner as shown in the drawings, serving, by resting against the edge of the sole, to determine the proper distance therefrom at which each of the nails is to be driven.

In the operation of this machine, the wire, after having passed into the transerrer, is next cut by the knife. Next, the piece severed, will be transferred to and directly underneath the driver, which, next descending upon the piece of wire, will force it into the sole. The workman next tilts and moves the machine

forward the proper distance for another nail to be driven, after which, he, by a downward blow on the head of the driver-carrier, causes another advance of the wire, and another piece of it to be removed from the strip and driven into the sole.

I claim the combination of the cammed projection or arm G , or its equivalent, with the shank B of the nail-driver a , and with other mechanism, substantially as described, or its equivalent, for feeding the strip of nail-wire along, the whole being so constructed, that during each downward movement of the said shank, the percussive force or blow employed for effecting such movement, shall put in operation the feeding-mechanism, so as to cause the wire to be fed forward, as explained.

LOUIS GODDU.
